UNITED STATES PATENT OFFICE

127,372

DESIGN FOR A CURTAIN FABRIC

James G. Hunniford, New York, N. Y., assignor to Paroma Draperies, Inc., New York, N. Y., a corporation of New York

Application April 5, 1941, Serial No. 100,166

Term of patent 3½ years

To all whom it may concern:

Be it known that I, James G. Hunniford, a citizen of the United States of America and a resident of the Borough of Manhattan, city, county, and State of New York, have invented a new, original, and ornamental Design for a Curtain Fabric, of which the following is a specification, reference being had to the accompanying drawing, forming a part thereof, in which the figure is a plan view of a piece of curtain fabric, showing my new design.

I claim:

The ornamental design for a curtain fabric, as shown.

JAMES G. HUNNIFORD.
